BY *Malcolm Ellis*

ATTORNEY.

UNITED STATES PATENT OFFICE.

AZARIAH Y. PEARL, OF WEST LEBANON, MAINE.

AUGER.

SPECIFICATION forming part of Letters Patent No. 788,941, dated May 2, 1905.

Application filed April 18, 1903. Serial No. 153,263.

To all whom it may concern:

Be it known that I, AZARIAH Y. PEARL, a citizen of the United States, residing at West Lebanon, in the county of York and State of Maine, have invented a new and useful Improvement in Augers, of which the following is a full, clear, and exact description, reference being had to the accompanying drawings, which form part of this specification.

10 My invention relates to augers for boring square and rectangular holes; and the same consists, essentially, in improved means and devices for removing the chips, and consists in features and details which will be more 15 fully explained and pointed out in the description of the drawings.

This invention consists in improvements upon the device shown and described in Letters Patent Nos. 505,844, October 3, 1893, 20 565,500, August 11, 1896, and 909,575, June 28, 1898.

The object of this invention is to provide a tubular conveyer for the rapid removal of chips from the work and consists of a hollow 25 tube connected to the upper end of the guide-block, through which the driving-shank passes centrally, and a spiral conveyer secured to said driving-shank and turning within the aforesaid tube, the said tube having an orifice 30 near its upper end for the discharge of the chips.

A further object of this invention is to provide an improved form of cutter-propeller, the same having an increased clearance between the blades to facilitate an easy discharge of the chips, together with other improvements which will appear in the following specification as follows, to wit:

Figure 1 is a side view of the auger, showing the side cutter-face, also the orifice in the tube for the discharge of chips. Fig. 2 is a vertical section on line 2 2 of Fig. 1. Fig. 3 is a detail view of the propeller and driving-shank, showing the spiral conveyer attached thereto. Fig. 4 is a detail section on line 4 4 of Fig. 2, showing the enlarged clearance-space in the guide-block.

In this invention the principal features and mode of operation are the same as shown and described in my previous patents above re-

ferred to, and consists, essentially, of a central shank 1, to the lower end of which is secured a suitable bit 2. The said bit 2 and the shank 1 have a bearing in the guide-block 3, which is square in cross-section, each side of 55 which is equal to the diameter of the bit 2, and cutter-wheels 4, secured on two opposite sides of the guide-block 3 by screws 5. These cutter-wheels 4 are separated from the guide-block 3 by thin metal washers 6. To the upper end of the guide-block 3 there is secured a tube 7, whose diameter is slightly less than the diameter of the guide-block 3. This tube 7 may be of any desired length, and near its upper end is a lateral orifice 8 for the discharge of chips. At the upper end of the tube 7 there is inserted a cup-shaped block 9, and a ring 10, of a diameter slightly less than the bore of the cup-shaped block 9, surrounds the shank 1 and is pinned thereto by a pin 11, 60 passing through the ring 10 and shank 1. Suitable holes 12 are provided through the side of the tube 1 and cup-shaped block 9 for the insertion and removal of said pin 11. Above the ring 10 there is a second ring 13, 65 surrounding the shank 1, and screws 14, securing tube 7, the cup-shaped block 9, and the ring 13 together, thereby forming a thrust-collar, both upward and downward, for the ring 10 and shank 1. The ring 13 has a conical orifice 15 at its upper end, and the shank 1 has a lateral orifice 16 communicating with the bottom thereof, so that oil poured in at 15 will enter through the orifice 16 and be discharged through orifice 17 for lubricating the cutter-wheels 4 in a manner substantially as described in my previous patents. Above the ring 13 there is placed a split ferrule 18 for taking the set-screw in the spindle of the drill or other press that operates this auger. The lower end of the shank 1 terminates in the propeller 19, provided with blades 20, which engage the teeth of the cutter-wheel 4. This propeller 19 differs from that shown in my previous patents by having the blades 20 grow thinner as they extend upward and also taper in toward the shank 1, thereby giving an increased clearance for the chips as they travel upward. (See Fig. 3.) The guide-block 3 instead of having an upper orifice for the discharge of 100

chips of cylindrical form and a diameter substantially the same as the diameter of the propeller is provided with an orifice which flares out in the direction of the cutter-wheel 4, as indicated in Fig. 4 at 21, forming a sort of inverted funnel, and this very materially assists in a free discharge upward of the chips and prevents clogging. After the chips have passed the blades 20 of the propeller 19 they are met by a spiral conveyer 22, which lifts them up the tube 7 until they come opposite the orifice 8, from which they are discharged.

The functions and operation of this tool being in all respects similar to those described in my previous patent, a description of those features will not be here repeated.

I claim as my invention—

1. An auger having a hollow shank, cutting-tools operatively connected thereto to form an angular bore, a non-rotatable guide-block having a tubular extension above, within which is a spiral conveyer secured to and operated by the said hollow shank, a thrust-collar secured to said shank above the spiral conveyer and thrust-bearing secured to the tubular extension from the guide-block, and an oil-orifice in the said hollow shank above said thrust-bearing, substantially as described.

2. An auger having a shank terminating in a propeller provided with blades having an increased clearance for operating cutting-tools to form an angular bore, a non-rotatable guide-block in which the shank is mounted, said guide-block corresponding in cross-sectional area and contour with the hole which the auger and cutting-tools are adapted to cut, substantially as described.

3. An auger having a non-rotatable guide-block, cutting-tools mounted in recesses therein and means for operating them, the said guide-block corresponding in cross-sectional area to the hole which the auger and cutting-tools are adapted to cut, a tubular extension above the said guide-block and a spiral conveyer within said tube for removing the chips.

4. An auger having a shank terminating in a bit and provided with a spiral conveyer for removing the chips, a non-rotatable guide-block through which the shank passes, a tubular extension above said guide-block within which the spiral conveyer operates, cutting-tools recessed within the sides of the guide-block and arranged to discharge their chips through the guide-block to the spiral conveyer within the tubular extension, substantially as described.

5. An auger for boring rectangular holes, cutting-tools rotatable in planes parallel to the direction of the hole, a rotatable shank terminating in a propeller for operating the cutting-tools, the blades of said propeller having increasing clearance in the direction of

the discharge of the chips from the cutting-tools, substantially as described.

6. An auger for boring rectangular holes, 65 comprising a shank terminating in a bit, a non-rotatable guide-block provided with an upper orifice formed like an inverted funnel for the discharge of chips, a tubular extension above said guide-block within which is a spiral 70 conveyer for the removal of chips discharged through said funnel-shaped orifice in the guide-block, cutting-tools recessed within the sides of the said guide-block so that they will discharge their chips through said guide-block and into the tubular extension to the spiral conveyer, and means for operating said cutting-tools from the shank, substantially as described.

7. An auger having a non-rotatable guide-block with recesses in the sides communicating with a tubular extension above, within which is a rotatable shank terminating in a bit and having a spiral conveyer secured thereto above the guide-block, cutting-tools mounted within the recesses in the sides of the guide-block and means for rotating the cutting-tools from the aforesaid shank, substantially as described.

8. An auger having a shank terminating in a propeller provided with blades having an increased clearance, cutting-tools operated by said propeller to form an angular bore, a non-rotatable guide-block in which the shank and cutting-tools are mounted, said guide-block 95 corresponding in cross-sectional area and contour with the hole which the auger and cutting-tools are adapted to make, substantially as described.

9. An auger having a shank terminating in a propeller provided with blades having an increased clearance and a taper toward the shank, cutting-tools operated by said propeller to form an angular bore, a non-rotatable guide-block in which the shank and cutting-tools are mounted, said guide-block corresponding in cross-sectional area to the hole which the auger and cutting-tools are adapted to make, substantially as described.

10. An auger having a shank terminating in a bit, a non-rotatable guide-block through which the said shank passes, cutting-tools recessed within the sides of the said guide-block and operatively connected to said shank, the said guide-block provided with an inverted funnel-shaped orifice extending upward through which the chips from the cutting-tools are discharged, substantially as described.
